UNITED STATES PATENT OFFICE.

PERCY ELMER TUCKER, OF BREMERTON, WASHINGTON.

APPARATUS FOR THE GENERATION OF STEAM.

1,270,990.

Specification of Letters Patent.

Patented July 2, 1918.

Application filed July 25, 1917. Serial No. 182,720.

To all whom it may concern:

Be it known that I, PERCY E. TUCKER, a citizen of the United States, and a resident of Bremerton, in the county of Kitsap and 5 State of Washington, have invented a certain new and useful Improvement in an Apparatus for the Generation of Steam, of which the following is a specification.

The present invention relates to a steam 10 generator, and has for its object the provision of an apparatus for generating steam by the combustion of a volatile fuel such as gasoline, kerosene and the like.

Other objects of the present invention are 15 to provide an apparatus which may be manually started or set in operation, which, after being started, is automatic in the control of the combustible gas and the water to be converted into steam; which is provided with 20 means for automatically controlling the generation of steam to maintain the desired pressure in the boiler or reservoir; and to provide a device comprising relatively few parts occupying but relatively small space.

25 The above, and various other objects and advantages of this invention will be in part described, and in part understood, from the following detailed description of the present preferred embodiment, the same being 30 illustrated in the accompanying drawings wherein:

Figure 1 is a side elevation of a steam generating apparatus constructed according to the present invention.

35 Fig. 2 is a fragmentary, enlarged, side elevation of the automatic means for controlling the generation of the steam.

Fig. 3 is a section view through the throttle which controls the flow of steam to the 40 operating engine.

Fig. 4 is a vertical sectional view through the check valve controlling the passage of generated steam into the reservoir or tank.

Referring to these drawings, 10 designates 45 a suitable reservoir or tank in which the steam generated may be collected and from which the steam may be distributed for use. The tank or reservoir is made of sufficient strength to withstand the desired steam pressure, and is provided with a suitable safety valve 11.

The steam is generated in a combustion 50 chamber 12 in the form of a cylinder which, as shown in the present instance, may be arranged vertically, and which is connected at

its lower end by pipe 13 to the reservoir 10. The pipe 13 is provided with a check valve 14, shown in detail in Fig. 4, which opens into the reservoir 10 to retain the steam under pressure therein. The casing of the 60 check valve 14 is provided with a web 15 dividing the casing and in which is formed a valve seat adapted to support a valve 16, the latter opening upwardly from the valve seat and normally held against the seat by a 65 spring 17. A cap 18 is mounted on the upper end of the valve casing 14 and receives the upper end of the spring 17 thereagainst. The valve 16 and the spring 17 may be withdrawn upwardly through the casing 14 by 70 the removal of the cap 18. The combustion chamber 12 is supported in any suitable manner, as by means of a bracket 19 projecting from the adjacent end of the reservoir 10.

Arranged adjacent to or near the combustion chamber 12 is a gas pump 20 connected at its intake to a carburetor 21 to which hydro-carbon fuel may be fed from tank 22 through pipe 23. A supply pipe 24 leads from the outlet of the pump 20 to preferably the upper end of the combustion chamber 12 and is adapted to supply gas under pressure thereto. A spark plug 25 of the usual construction is secured in the upper head of the combustion chamber 12 for 85 igniting the compressed gas in the chamber, as hereinafter set forth.

The pump 20 is operated by a reciprocating steam engine 26 arranged, preferably, in tandem with the pump 20 and the two being 90 connected by a common piston rod 27. The piston rod 27 may be provided with a pair of spaced-apart projections 28 adapted to strike a rocker arm 29 connected at its upper end to a valve rod 30 for actuating the 95 valves of the engine 26. A bracket plate 31 is secured across the upper portions of the engine 26 and the pump 20, and an operating lever 32 is pivoted intermediate its ends to the bracket plate 31 and projects at its lower 100 end into engagement with the piston rod 27, the lever 32 being forked at its lower end and suitably connected to the piston rod by a pin 33. The upper end of the lever 32 is socketed for the reception of a handle 34 105 which may be employed in starting the apparatus.

The bracket plate 31 is also provided, near its end adjacent the pump 20, with a rocker arm 35 pivoted at its lower end to the plate 110

31 and connected by a rod 36 to the upper end of the lever 32. The rod 36 is pivoted to the lever 32 at one end and is adjustably and pivotally connected to the rocker arm 35 at its opposite end by means of an adjustable bolt 37 or the like. Secured preferably on the upper portion of the pump 20 is a relatively small water pump 38 the piston 39 of which is connected by link 40 to the rocker arm 35 near the lower end of the latter to actuate the pump 38 upon the movement of the arm 35. The pump 38 is connected at its outer end, opposite to the piston rod 39, to a water supply pipe 41 having a non-return check valve 42 therein, and which terminates in a rose or spray-nozzle 42' arranged within the lower portion of the combustion chamber 12. A water supply pipe 43 leads from a water tank 44 and is provided with a non-return check valve 45 therein adjacent to the pump 38. The pipe 43 opens into the pipe 41 at a point between the valve 42 and the pump 38.

The spark plug 25 has one electrode 25 grounded in the apparatus through the combustion chamber 12, and the opposite electrode is connected by wire 46 to one end of the primary winding of a transformer or inductorium 47, the opposite end of the primary winding of which is grounded, as at 48. The secondary winding of the transformer 47 has one terminal connected by wire 49 to a battery or exciter 50. The opposite terminals of the transformer 47 and the battery 50 are connected by leads 51 and 52 to fixed and movable contacts 53 and 54. The fixed contact 54 is secured to the inner end of the pump 20 and has connection with the lead 52. The movable contact 53 is secured to the lower end of the lever 32 in position to engage the fixed contact 54 when the lower end of the lever is swung toward the pump 20 in the act of compressing the gas in the combustion chamber 12.

The steam engine 26 is operated by steam which is generated and collected in the tank 10, the steam being carried through a steam pipe 55 and controlled by a throttle valve 56 which is arranged in the pipe preferably adjacent to the engine 26. As shown in Fig. 3, the throttle valve 56 comprises a casing connected at opposite ends in the pipe 55 and which has a transversely extending shell or partition 57 therein of cylindrical form. The shell 57 has in its upper and lower sides perforations adapted to align with correspondingly formed perforations in a hollow cylindrical plug 58 adapted to turn within the shell 57. The plug 58 is provided at one end with a stem 59 projecting through the adjacent side of the throttle valve 56 and to which is secured an operating arm 60, the latter having a longitudinal slot in its outer end. A frame 61 is secured to the engine 26 and rises therefrom into a position above the

throttle valve 56 and at one side thereof. A pressure regulating cylinder 62 is mounted vertically upon the upper end of the frame 61, the cylinder 62 having a piston 63 therein, as shown in detail in Fig. 2, and provided with a depending piston rod 64 which is connected to the arm 60 by a laterally extending pin 65 projecting into the slot of the arm. The upper end of the cylinder 62 is connected to the main steam line 55 by a bypass pipe 66, the steam entering the top of the cylinder 62 is adapted to force the piston 63 downwardly therein. A drain cock 67 may be mounted in one side and at the lower end of the cylinder 62. The lower end of the piston rod 64 is provided with a head 68 to which is secured the upper end of an expansion spring 69. The lower end of the spring 69 rests upon a hand wheel 70 which is supported upon a depending externally screw-threaded stem 71 having threaded engagement through the lower end of the frame 61. By turning the hand wheel 70 in opposite directions the stem 71 is raised and lowered so as to increase and decrease the tension of the spring 69 and produce an adjustable resistance for the piston 63 against steam entering the upper end of the cylinder 62.

In operation, when it is desired to start the apparatus it is only necessary to insert the handle 34 in the socket of the lever 32 and reciprocate the latter sufficiently to actuate the pump 20 for drawing a charge of gas from the carburetor 21 and ejecting the same under pressure into the combustion chamber 12. The operation of the lever 32 also operates the water pump 38 and water under pressure is forced through the spray nozzle 42' into the lower end of the combustion chamber 12. As the lower end of the lever 32 moves forwardly to force the charge of gas into the combustion chamber 12, the contact 53 approaches the fixed contact 54, and upon completion of the force stroke the circuit is completed through the transformer 47 and a spark is produced at the plug 25 to thus ignite the charge delivered to the combustion chamber. The pump 38 is actuated prior to the operation of the gas pump 20 so as to deliver a fine spray of water into the lower end of the chamber 12, for by first injecting the water into the combustion chamber 12, the water is primarily heated, and may then be more readily converted into steam than if the water and gas be simultaneously delivered into the chamber. Furthermore, the relatively cold water when brought into contact with the charge without preliminary heating, tends to condense the fuel and retard the consumption of the same. The burning ignited gases in the chamber 12 practically instantly convert the sprayed water into steam, and the combined pressures of the steam and the burning gases

expand sufficiently to force the major portion of the same past the check valve 14 against the tension of spring 17, and into the tank 10.

As soon as sufficient pressure of steam has been obtained in the tank 10, the steam passes through the pipe 55, the throttle valve 56, and into the engine 26 for driving the pump 20 and the mechanism connected thereto. The spring 57 is adjusted to exert 5 the desired tension upon the piston 63, and when the pressure of the steam in the tank 10 reaches the desired limit, the steam in the bypass pipe 66 overcomes the tension of the spring and moves the piston 63 and the 10 arm 60 downwardly to thus close the throttle valve 56 proportionately to the downward movement of the piston 63. As soon however as the pressure in the tank 10 drops, the spring 69 opens the throttle valve 56 15 and the engine 26 is again started to operate. The steam may be let off from the boiler 10 for any suitable purpose, such as for operating other steam engines, turbines or the like and to carry off the steam a pipe 72 may 20 be connected to the pipe 55, and any suitable controlling means may be employed in the pipe 72.

It is of course understood that various changes and modifications may be made in 30 the details of construction of the above specifically described parts without departing from the spirit of this invention, such changes and modifications being restricted only by the scope of the following claims.

35 I claim:

1. In an apparatus for the generation of steam, the combination of a reservoir, a combustion chamber communicating with the reservoir, means for intermittently delivering charges of combustible gas to said chamber, means for intermittently feeding water in small quantities to the chamber alternately relatively to the charges of gas, and means for igniting the gas whereby said 40 gas when burning is adapted to convert the preheated water into steam and force the same by its expansion into the reservoir.

2. In an apparatus for the generation of steam, the combination of a reservoir, a combustion chamber communicating with the reservoir, fuel feeding means adapted to deliver a charge of gas to the combustion chamber, water feeding means adapted to deliver a charge of water into the combustion 45

chamber, operating means for alternately actuating said fuel and water feeding means, and ignition means controlled by the operating means for exploding the charge of fuel when in the combustion chamber.

3. In an apparatus for the generation of steam, the combination of a reservoir, a combustion chamber communicating with the reservoir, a fuel feeding pump connected to the combustion chamber, a steam engine for operating said pump, a water feeding pump 60 communicating with the combustion chamber, a connection between said pumps to alternately actuate the same upon the operation of the steam engine, an ignition device connected to the combustion chamber for 65 igniting the gas therein and having connection with said engine adapted to be actuated by the same subsequent to the delivery of gas to the combustion chamber, and adjustable controlling means connected to the engine for operating the latter to maintain a 70 predetermined steam pressure in said reservoir.

4. In an apparatus for the generation of steam, the combination of a reservoir, a combustion chamber communicating with the reservoir, a gas feeding pump communicating with the combustion chamber, a carburetor connected to the intake of the gas pump, a steam engine connected to said gas 80 pump, a water pump for operating the same, a water pump 85 communicating with the combustion chamber, a connection between said pumps to alternately actuate the water pump with respect to the operation of the gas pump, said 90 connection including a rocking lever having a socketed portion, a handle adapted to be engaged in said socketed portion for manually operating the pump during initial operation of the machine, ignition means for 95 exploding the gas in the combustion chamber, said ignition means including fixed and movable contacts associated with said pumps and said connecting means therefor for igniting the gas subsequent to the delivery 100 of the same to the combustion chamber, a steam line between the reservoir and said engine, and adjustable controlling means in said steam line adapted to actuate the engine upon a decrease in the predetermined steam 105 pressure for the reservoir.

PERCY ELMER TUCKER.
